UNITED STATES PATENT OFFICE.

JEROME W. WETMORE, OF ERIE, PENNSYLVANIA.

WAGON BOLSTER-SPRING.

SPECIFICATION forming part of Letters Patent No. 252,824, dated January 24, 1882.

Application filed May 14, 1881. (No model.)

To all whom it may concern:

Be it known that I, JEROME W. WETMORE, a citizen of the United States, residing at Erie, in the county of Erie and State of Pennsylvania, have invented a new and useful Improvement in Wagon Bolster-Springs, of which the following is a specification.

My invention relates to torsion-springs for bolster-wagons; and the objects of my improvement are, first, to use straight spring-bars without friction-joints; second, to support the forward and back pressure of the load and lessen this pressure on the stakes; third, to allow the load to rest temporarily on the bolster in case of very great weight and concussion, to keep the spring-board nearer the bolster; and, fourth, to bring the entire steel of the main bolster-spring into use under both light and heavy loads. I attain these objects by the devices illustrated in the accompanying drawings, in which—

Figure 1 is a perspective view of the axle and bolster of a lumber-wagon with the springs applied; Fig. 2, a vertical section of the spring and lever-arm through the line xx , Fig. 1, with a partial view of one of the bearings beyond them; Fig. 3, the same view with the arms of the springs depressed; Fig. 4, a vertical section through yy , Fig. 1, one of the three sets of supporting-arms; Fig. 5, a perspective view of one of the six bearings or holding-blocks e , and lever-arms of the springs with a section of the spring a ; Fig. 6, another form of the outer end of the arm; Fig. 7, another form of the end of the elliptical spring. The tongue i hinges in the slot j . Figs. 8 and 9 represent the torsion-spring rod used as the equivalent of the spring D ; Fig. 10, a section across the slots in the holding blocks and arms, showing the slots narrowest at the middle except in

H is the bolster; K K, the axle. The holding-blocks e are riveted to the plates G, as shown at m , Fig. 5. The bar a is held fast by a wedge or set-screw in the middle holding-block. 45 The spring-board E, Fig. 1, passes over the top of the springs D D. The arms and bearings F and c are of malleable iron, and are slipped to their places on the bars. If the spring-bar a bends down too much under a 50 heavy load, concave iron blocks will be placed on the bolster a little below the base of each lever n , Fig. 2, rounded as at r , Fig. 5, the blocks being held by screws or a strap passing over the bolster. The cuttings of the ends of 55 the half-elliptical springs at i and j , to make the slot or tongue, are turned up to make friction-bearings on the arm. The end g , Fig. 5, may be bent after the spring D is in place to hold it. The arm S, Fig. 8, will be about half 60 the length of the arm F, and its angle with a horizontal line about double of the angle of the arm F with that line. The load rests on E, Fig. 2, and the operation of the springs is obvious from inspecting Figs. 2, 3, and 5. 65

What I claim is—

1. The spring-bar a , when placed by the side of the bolster and supported in the middle and at each end without pivot-bearings, and connected by the arms F between the bearings 70 with the bolster-board E, substantially as described.

2. The spring-supports $e e$, with connecting-plate G, in combination with the spring a , substantially as described. 75

3. The spring-bar a , bearings $c c$, and arms F, in combination with the arms D and bolster-board E, substantially as described.

JEROME W. WETMORE.
